CARTRIDGE FEED SYSTEM

Charles H. Morse, Herkimer, and Homer W. Young, Ilion, N.Y., assignors to Remington Arms Company, Inc., Bridgeport, Conn., a corporation of Delaware

Filed Dec. 8, 1959, Ser. No. 858,099

3 Claims. (Cl. 42-17)

This application is directed to the system for controlling the release of cartridges from the magazine of a repeating rifle and guiding such cartridges unerringly into the chamber. The invention is illustrated in its application to the firearm shown in the application of Leek and Morse, Serial No. 780,573, filed December 15, 1958.

In an autoloading rifle the time available for effecting the transfer of cartridges from magazine to barrel chamber is very short and the moving parts function at high rates of speed. Any failure to accurately control the presentation of and introduction into the chamber of cartridges can result in various sorts of malfunctions, including, at one extreme, the accidental firing of a jammed cartridge and, at the other extreme, in such shoving or deformation of bullet and/or cartridge case as to substantially reduce the accuracy of shooting.

Conventional cartridge feeding systems have involved positioning the cartridge on various ramps or lifting devices in a position at least partially in front of the breech bolt so that, as the breech bolt returns to breech closing position, it will engage the head of the cartridge and push it free from the lifters and/or detents employed and seat it in the barrel chamber.

We have discovered that by proper control of the release of the cartridge and proper design of the positioning ramps, we can release a cartridge during rearward movement of the breech bolt and spring impel it toward and partially into the chamber so that as the breech bolt rebounds from the rearward extremity of its cyclic movement, it will overtake a cartridge which is either already in movement toward the chamber or has already been aligned and partially seated in the chamber.

The exact nature of the invention as well as other objects and advantages thereof will more fully appear by reference to the following specification referring to the attached drawings in which:

FIG. 1 is a longitudinal, vertical sectional view taken through the receiver section of a firearm embodying the invention.

FIG. 2 is a longitudinal, horizontal sectional view taken in the plane 2-2 shown on FIG. 1.

FIGS. 3, 4 and 5 are partial views corresponding generally to FIG. 1 but showing the elements in the positions they occupy at different phases of the operating cycle.

FIG. 6 is a side view of the cartridge feed insert.

FIG. 7 is a top view of the cartridge feed insert shown in FIG. 6.

FIG. 8 is a partial longitudinal horizontal sectional view taken in the plane 8-8 in FIG. 1.

Referring to the drawings by characters of reference, it will be seen that our invention is embodied in a blow-back type of autoloading firearm more fully disclosed in the parent application. This firearm features a unitary assembly of molded nylon or other dimensionally stable, self-lubricating thermoplastic material forming buttstock section, receiver section, and forestock section. The present invention relates only to elements which are housed within the receiver section and the illustration is therefore substantially confined to this area. Although the invention is particularly adapted to use with autoloading actions, it should be obvious that it will function

2

as well with an action in which the reciprocation of the breech bolt is performed manually.

The firearm illustrated has a receiver section 1 molded of thermoplastic material in two mirror image halves which are secured by a welded joint at the meeting faces. A reciprocating breech bolt 2 is slidably guided in tracks formed in the receiver section, and a magazine tube 6 provided with a spring-urged follower 31 having the basic dimensions of a dummy cartridge extends through the buttstock, not shown, into the receiver portion.

This receiver portion is formed to define a cartridge feed passage 33 and a feed ramp 34 in substantial prolongation of the magazine tube. A cartridge stop 35 is pivotally supported on a cartridge stop pin 36 and provided with a cartridge stop spring 37 which urges the end of the cartridge stop to extend into the cartridge feed passage 33 in position to intersect the head or rim of a cartridge case and prevent the delivery of more than one cartridge at a time to the feed ramp 34. The cartridge stop is operated by means of an arm 38 which extends upwardly into the path of the breech bolt in position to be released from the control of a cam surface 2a in the breech bolt whenever the breech bolt is displaced rearwardly by any substantial amount from the position shown in FIG. 1. It should be apparent that whenever the breech bolt is rearwardly displaced, the cartridge stop will be raised into the feed passage 33. However, the extent of the projection into the feed passage is not enough to intercept and stop forward movement of a cartridge until the rim thereof engages solidly against the cartridge stop. Thus, a following cartridge in the tubular magazine or the leading portion of the magazine follower itself will remain free to apply spring force to urge the cartridge in the feed passage, up the feed ramp, and partially into the chamber of the barrel in which it will be pushed home by the returning breech bolt. The following cartridge, or the magazine follower, will, however, be positively stopped by the cartridge stop 35 in such a position that the forward movement of the bolt cannot be obstructed and will not be released for further movement until such time as the bolt has substantially reached its breech closing position and the cam surface 2a has overridden the arm 38.

In the cartridge feed passage 33 we have provided a metallic cartridge feed insert 40 formed generally to define a U-shaped channel open at the top and ending adjacent the surface of the bullet feed ramp 34 (see FIGS. 6 and 7). The upper edges 41 of the rear portion of the cartridge feed insert 40 are spaced laterally by a distance which is somewhat greater than the diameter of the body of the cartridges to be used and somewhat less than the diameter of the rim of the head of the cartridge. These edges are inclined upwardly at an angle only a little less than that defined by the bullet feed ramp 34 so that as a cartridge advances through the feed passage, the bullet end is raised by the ramp 34 and the rim by the edges 41 so that the cartridge is presented to the chamber 3 of the barrel 4 in substantial parallelism with the axis thereof.

The lower rear circumferential edge of the cartridge feed insert 40 defines a semi-annular shoulder 42 spaced from the lower face of the bolt by a distance less than the diameter of the rim of a cartridge and adapted to engage the rim of a cartridge and to prevent further forward movement thereof while such cartridge is held down into the cartridge feed insert as by the presence of the lower surface of the bolt 2 above the shoulder 42.

Considering the operation of the cartridge feed system, it will be apparent that when the cartridge A shown in the chamber in FIG. 1 is fired the breech bolt 2 will be retracted rearwardly and that the cartridge A will be

ejected by engagement of the left hand portion of the rim against the ejector blade 43 (see FIG. 8) projecting into the receiver. Shortly after ejection of the fired case, the front edge of the breech bolt will pass to the rear of the semi-annular shoulder 42, releasing the cartridge B from any further restraint and permitting it to be urged forward by the force exerted by the magazine spring 44 and follower 31 acting through the cartridge C. FIG. 3 shows the parts in position just prior to the release of the cartridge B with the cartridge stop 35 raised into the cartridge feed passage in position to intercept the rim of the cartridge C. The sudden release of the cartridge B as the bolt is retracted permits that cartridge to be snapped forwardly by the magazine spring. As a result, and as shown in FIG. 4, the cartridge B will be projected forwardly to at least start the bullet of the cartridge B in the chamber of the barrel, it being recalled that the bullet feed ramp 34 and the edges 41 of the cartridge feed insert accurately guide the cartridge in that direction.

A bullet feed guide 45 is pivotally secured to the breech bolt and extends forwardly over the rear portion of the barrel to provide a ramp surface 46 terminating closely adjacent the mouth of the barrel chamber. A bullet feed guide spring 47 is mounted in the receiver cover 48 and lies upon the bullet feed guide to yieldingly hold it down on the barrel ramp. As best seen by the dotted line position of a cartridge B₁ in FIG. 4, if due to any unusual circumstance the cartridge B tends to be released from the magazine bullet high the bullet portion will be engaged by a formed depression 49 in the bullet feed guide and deflected downwardly to enter the chamber. Similarly, the dotted line position B₂ shows a cartridge which for some reason has not been snapped clear into the chamber and lies upon the bullet feed ramp and cartridge feed insert in position to be pushed into the chamber by the bolt.

In any case, a cartridge being released from the magazine is surrounded on three sides by (1) the bullet ramp 34 and cartridge feed insert 40; (2) the longitudinally extending ejector blade 43; and (3) by the overlying bullet feed guide 45. As a result of the close control maintained, the cartridges have virtually no opportunity to go any place but properly into the chamber.

FIG. 5 carries the sequence of operations one step

further and shows the cartridge B nearly seated in the chamber with the cartridge stop 35 just cammed down by the face 2a of the bolt to release the cartridge C into the cartridge feed insert 40 where it comes to rest trapped between the lower face of the bolt and the semi-annular shoulder 42 on the rear end of the cartridge feed insert.

Obviously the cycle described can be repeated for any number of cartridges delivered by the tubular magazine and when the last of such cartridges has been delivered 10 into the cartridge feed insert as shown in FIG. 5, the magazine follower itself supplies the necessary feeding thrust and is itself stopped by the cartridge stop.

We claim:

1. In a repeating firearm having a barrel, a receiver, 15 a breech bolt longitudinally reciprocable in said receiver, a tubular magazine extending from a position beneath said breech bolt, a spring urged follower in said magazine urging cartridges therein to a position beneath said breech bolt, a cartridge feed insert defining forwardly and 20 upwardly inclined elevator surfaces to elevate a cartridge as it passes therethrough, a forwardly and upwardly inclined bullet feed ramp, and cartridge stop means to control the release of cartridges from said magazine, the improvement comprising a bullet feed guide pivotally attached to the breech bolt and extending forwardly therefrom over the top surface of the barrel to form a reciprocating closure of the upper side of the space between the breech bolt and the barrel.

2. The combination described in claim 1, the upper 30 face of said barrel being cut away to define a flattened ramp engaged by said reciprocating bullet feed guide.

3. The combination described in claim 2, including 35 spring means exerting a yielding pressure tending to maintain said bullet feed guide in close engagement with said flattened ramp on the barrel.
